UNITED STATES PATENT OFFICE

BEN H. WILSON, OF TOLEDO, OHIO, ASSIGNOR TO OWENS-ILLINOIS GLASS COMPANY, OF TOLEDO, OHIO, A CORPORATION OF OHIO

DESIGN FOR A JUG

Application filed March 29, 1930. Serial No. 35,070. Term of patent 14 years.

To all whom it may concern:

Be it known that I, BEN H. WILSON, a citizen of the United States, residing at Toledo, in the county of Lucas and State of Ohio, have invented a new, original, and ornamental Design for Jugs, of which the following is a specification, reference being had to the accompanying drawing, forming a part thereof.

In the drawing:

The figure is a side elevation of a jug, showing my new design.

The jug is substantially round in cross-section and the view from the opposite side would present an appearance similar to the side shown.

I claim:

The ornamental design for a jug, substantially as shown and described.

Signed at Toledo, in the county of Lucas and State of Ohio, this 27th day of March, 1930.

BEN H. WILSON.
